UNITED STATES PATENT OFFICE.

REINHARD E. BARTELS, OF LYNN, MASSACHUSETTS.

APPARATUS FOR ATTACHING SHOE PARTS.

Application filed June 9, 1922., Serial No. 567,068.

To all whom it may concern:

Be it known that I, REINHARD E. BARTELS, a citizen of the United States, residing at Lynn, in the county of Essex and State of Massachusetts, have invented new and useful Improvements in Apparatus for Attaching Shoe Parts, of which the following is a specification.

This invention relates to apparatus for attaching shoe parts, being more particularly intended for attaching shank stiffeners to soles or to shank pieces of turn shoes and is adapted to be used in connection with a foot power hammer.

The present application is a continuation in part of application Serial No. 376,633 Filed April 26, 1920 for apparatus for locating shank stiffeners in shoe soles.

The break line on the turn shoe shank has no definite location and is arbitrarily determined by the manufacturer. That is, in placing the shank in the shoe, the manufacturer may extend the forward end of the shank as far forward of the break line of the shoe as his fancy or judgment may dictate. In view of the arbitrary location of the break line as set forth above, the position of the forward end of the shank stiffener on the shank may be determined by measuring rearwardly from the forward end of the shank a distance equal to the distance of the break line therefrom plus the distance that the forward end of the stiffener is to be positioned back of the break line. After ascertaining this point for one shank of a lot to be made up in a certain way, the point may be located mechanically for the rest of that particular lot by using the apparatus of this invention.

For a more complete understanding of this invention reference may be had to the accompanying drawings in which:

Figure 1 is a top plan of the apparatus.

Figure 2 is a section on line 2—2 of Figure

1. Figure 3 is a section on line 3—3 of Figure 2.

Figure 4 is a plan of a shank piece with a stiffener thereon.

Figure 5 is a section of the same molded for incorporation in a shoe.

Figure 6 is a side elevation of a stiffener.

Figure 7 is a side elevation of a foot power hammer for use with the apparatus.

Figure 8 is a fragmentary front elevation partly in section of the same.

Figure 9 is a front elevation of a modified form of hammer.

Figure 10 is a plan of an apparatus for use in attaching stiffeners to shoe soles.

Figure 11 is a fragmentary section on line 11—11 of Figure 10.

Figure 12 is a perspective of the shank stiffener.

Figure 13 is a detail elevation to enlarged scale of a modified form of hammer.

The turn shoe shank is in the form of a flat blank while the stiffener is preferably formed prior to attachment to the shank with a longitudinal ridge extending to within a short distance of the end thereof.

A form of stiffener to be used with a turn shoe shank is illustrated at 42 in Figure 6, the longitudinal ridge being indicated by the reference numeral 43 and the securing tines by the numeral 44. It will be noted that these tines extend from the opposite side of the shank stiffener from that on which the ridge is located.

Referring to Figures 1 to 3 and 7 to 9, 50 indicates a flat plate on which the turn shoe shank is to be placed and which is provided with means for holding the shank stiffener in fixed position thereon. This means comprises a support for the shank

stiffener preferably formed by cutting a slot 51 (see Figures 2 and 3) longitudinally through the plate and covering said slot with a thin sheet of metal 52, as brass, aluminum, or the like, formed with a longitudinal depression 53 therein. The purpose of this depression is to receive the ridge of the shank stiffener when said stiffener is placed on the plate, as will hereinafter be set forth. Bordering the slot 51 on three sides is a U-shaped brace member 54, which serves to hold the sheet of metal in place and prevents lateral displacement of the shank stiffener, when placed on the plate.

This brace member may be formed integral with the plate but is preferably made separately and attached thereto in some suitable manner as by a screw or the like, see Figures 1 and 2 of the drawings).

Located a short distance in front of the brace member 53 is an abutment member 55 against which the forward end of the shank stiffener abuts when placed between the arms of the U-shaped brace member in position to be attached to the shank. The U-shaped member 54 may be made longitudinally adjustable to adapt it to confine the

shank stiffener in its position abutting against the member 55 if so desired.

The plate is also provided with suitable guide members for positioning the shank in proper relation above the shank stiffener to be attached thereto. There may be any suitable number of these guide members, three being shown in Figure 1, comprising an end guide member 56 in front of abutment 55, and two side guides 57 and 58. The guide members are L-shaped, having long arms which lie against the plate, and short abutment arms 56^a, 57^a, and 58^a which project upwardly therefrom forming abutments 10 against which the shank is placed in positioning it above the shank stiffener. The guides are provided with suitable means whereby they may be adjusted to a shank of any dimensions and to position the same 15 with its longitudinal median line directly above that of the stiffener. As shown in Figure 1, this means comprises slots 45 in the long arms of the guide and set screws 46 located in said slot and screwed into the 20 plate.

With shanks to be treated alike, the operation is as follows: The distances on the shank relative to the break line, as indicated above is determined and measured 25 forwardly on the plate from the rear of the abutment member 55 and abutment arm 56^a placed at this point, and the side guide members 57 and 58 are set so as to position the shank above the shank stiffener in order 30 that the longitudinal center lines of both of these members will coincide. When the device is so set, a shank stiffener is slipped into place with the tines extending upward and a shank is placed thereabove abutting the 35 brace members in the manner, as set forth above, and is struck with a hammer at a point above where the tines are located.

In Figures 7 and 8, are shown one form 40 of foot power hammer with which this form of my plate is adapted to be used. The foot power hammer comprises a base member 60 mounted on a suitable support as on a table or bench 61, which is in turn supported at some distance from the floor or ground by 45 means of legs 62. Extending upwardly and then forwardly from the base member is an arm 64 terminating in a sleeve 65. Slidably mounted in this sleeve is a hammer rod 63 on the lower end of which is a hammer 47. 50 The hammer rod 63 is guided in its sliding movement in the sleeve 65 and prevented from rotation therein, by means of a lug 65^a, riding in a groove 65^c in the rod 63. The lug 65^a is formed integral on the end of a 55 set screw 65^b screwed into an aperture in the sleeve 65.

The plate 50 is so positioned on the base 60 of the machine that when a stiffener is placed on the plate as indicated above, the 65 tines on the front end thereof will be di-

rectly beneath the hammer 47, and may be secured in this position by any suitable means as by a bolt 66.

The hammer is actuated by means of the following mechanism: A lever 69 is pivoted 70 on the arm 64 between ears 70, and is provided with a forwardly extending arm 68 and a rearwardly and downwardly extending arm 71. The upper end of the hammer rod 63 is slotted at 67 to receive the forward end of arm 68 which rides loosely therein. The arm 71 is curved forwardly at its lower end at 72, and extends under the bench or table into position to be conveniently struck by the foot of the operator. 75 When the operator strikes the member 72 the hammer is brought down upon the shank, driving the tines of the shank stiffener therethrough thereby attaching the two members together. A buffer 75 of rubber 80 or other resilient material may be so placed on the table as to minimize the shock of the lever arm 71 when it abuts against the table.

In practice, it is desirable in this operation to attach the shank support to a turn shoe shank only at the forward end and securely enough for the two members to remain attached in proper position relative to each other, until the shank, which at this stage is in the form of a flat blank, can be molded into a suitable shape to be placed in a shoe. The shank stiffener is fastened securely in place in the molding of the shank to form. 90

Under some circumstances, however, it is desirable to attach the shank stiffener to the shank at both ends in the initial operation and by a single operation of the machine. I accomplish this by using a double hammer, 95 such as is illustrated at 76 of Figure 9, with the two heads 77 and 78 spaced a distance apart equal to the distance between the forward and rearward tines of the shank stiffener. 100

In Figures 10 and 11 is shown a form of apparatus by which shank stiffeners, as shown in Figure 12, may be attached to shoe soles by means of a hammer such as shown in Figures 7, 8, and 9. A plate 10 115 is recessed at 90 so as to receive and retain in position a shank stiffener of the form shown in Figure 12 with its sole-attaching tines extending upwardly. A locating plate 17 is slidable in guides 20 and 21 on this plate in a direction longitudinal of the recess 90 and determines the position of the sole shown in dotted lines in Figure 10 lengthwise of the recess, while a laterally 120 adjustable guide 93 may be used to center the sole laterally relative to the stiffener in the recess 90. The plate 17 may be clamped in fixed position by means of a bolt clamp 125 26 having an operating handle 27.

One of the guides, as 20, is preferably 130

provided with a scale, the graduations conforming to shoe sizes, while the locating plate may have incorporated thereon graduations corresponding to styles so that by bringing the proper style mark into registry with the size mark, plate 17 is positioned properly to receive a sole of that style and size correctly positioned relative to the stiffener in the recess 90. It is also evident that plate 50 and guide 56 of the apparatus for turn shoes shown in Figures 1 to 3 and 7 to 9 may have similar size and style graduations thereof if desired.

Where the sole or shank piece is made of comparatively dense material such as certain grades of leatherboard, a hammer with a solid striking face cannot be used satisfactorily, the attaching tines being crushed or bent down by the hard material without penetrating it sufficiently to become properly attached. In such cases the hammer may be formed as shown in Figure 13 in which the striking element 470 is provided with a transverse slot 471 positioned to bear on the sole or shank piece directly above the tines. This construction furnishes a recess which permits the material over the tines to give way when the hammer strikes so that the tines are permitted to pass therethrough. This construction, of course, is applicable to both the single and double hammers above described.

Having thus described embodiments of this invention it should be evident to those skilled in the art that many changes and modifications might be made therein without departing from its spirit or scope as defined by the appended claims.

I claim:

1. A device for attaching a shank stiffener to a shank in a desired position thereon, comprising a plate with means thereon for holding the stiffener in fixed position, means for positioning the shank above said shank stiffener in a predetermined position relative to said shank stiffener, and power means associated with said plate for attaching said stiffener to said shank.

2. A device for attaching a shank stiffener provided with attaching tines to a shank in a desired position thereon, comprising a plate with means thereon for holding the stiffener in fixed position, means for positioning the shank above said shank stiffener in the desired position relative to said shank stiffener, and a power hammer associated with said plate in such position that the hammer may be brought down on said

shank to force the tines of the shank stiffener through the shank for attaching the parts together.

3. An apparatus of the class described, comprising means for holding in relatively assembled positions two members comprising a shoe part and a stiffener, said stiffener having attaching elements at each end, and a hammer having a pair of spaced striking heads actuatable to strike one of said members opposite the attaching means at both ends of said stiffener to fasten said members together.

4. An apparatus of the class described comprising means for holding in relatively assembled relation a pair of shoe parts, one of said parts having spaced elements for attaching it to the other of said parts, a hammer having a pair of spaced striking heads movable toward and from said parts opposite said elements, and a lever engaging said hammer and actuatable by the operator to cause said hammer to strike said parts and attach them by means of said elements.

5. An apparatus of the class described, comprising means for holding in relatively assembled relation a pair of shoe parts, one of said parts having an element constructed to penetrate the other of said parts to attach said parts together, and means for forcing said parts together including a member for engaging the other of said parts recessed opposite said element.

6. An apparatus of the class described, comprising means for holding in relatively assembled relation a pair of shoe parts, one of said parts having an element constructed to penetrate the other of said parts to attach said parts together, and a hammer actuatable to strike said other part to cause such penetration, said hammer being recessed opposite said element to permit the material of said other part to yield to the passage of said element.

7. A device of the class described comprising a plate having a slot therein, a cover for said slot comprising sheet material pressed to conform to the convex face of a shank stiffener molded to a lateral curvature and having upwardly extending attaching tines, means for holding a shank above said stiffener in predetermined relation thereto, and means to force said shank against said stiffener to cause said stiffener to become fixed thereto by said tines.

In testimony whereof I have affixed my signature.

REINHARD E. BARTELS.
